APPARATUS FOR INDICATING LOCATION
OF METALLIC PARTICLES IN FIBROUS
BODIESKeith L. Orser, Auburn, N. Y., assignor to Colum-
bian Rope Company, Auburn, N. Y., a corpora-
tion of New York

Application June 29, 1945, Serial No. 602,382

2 Claims. (Cl. 175—183)

1

This invention relates to improvements in indicator mechanisms and particularly to a mechanism for indicating the presence and location of metallic particles in bodies of materials such as reinforcing or filler material for moldable plastics compositions.

As is well known in the present day art of high pressure plastics molding it is the general practice to combine with the plastics, commonly called the binder, a reinforcing material, usually referred to as the filler, which imparts to an article molded from such a composition greater strength to resist sudden shocks or impacts than is possessed by an article molded from the plastics alone. One of the various types of filler materials that have been used is vegetable fibers and to facilitate handling such filler material it has been the practice in some instances to prepare comparatively long fibers in the form of a bat or web and pass the same through a standard textile needling machine which results in the formation of small tufts or groups of fibers throughout the web to more or less loosely interlace the fibers and substantially stabilize the web. Such preparation of the fibers for plastics compositions is more fully shown and described in United States Letters Patent No. 2,249,888, dated July 22, 1941. It frequently occurs, however, that the needles of the needling machine break off and become embedded in the needled bat of fibers so that there is great danger of the highly finished surfaces of the mold used in molding a composition being scratched or damaged and rendered practically worthless. For this reason it is highly desirable to detect and remove broken needles or other metallic bodies that may become embedded in the web of fibers and the primary object of the invention is to facilitate the removal of these metal particles by providing a mechanism which will automatically mark or denote on the web the location of such metallic particles embedded therein.

A further object is to provide an indicating mechanism wherein the web of filler fibers is fed in a continuous length past a normally inoperative marking device which is adapted to be rendered operative by the closing of the electrical circuit for an electric motor which actuates the means for feeding the web past the marking device.

2

With these and other objects in view, the invention consists in certain details of construction and combinations and arrangements of parts, all as will hereinafter be more fully described and the novel features thereof particularly pointed out in the appended claims.

In the accompanying drawings:

Figure 1 is a side elevational view of an apparatus embodying the present invention, the electrical equipment which forms no part of the invention being shown schematically;

Fig. 2 is a detail plan view of the driving connections between the web feeding means and the motor for driving the latter;

Fig. 3 is a wiring diagram for the apparatus illustrated in Fig. 1;

Fig. 4 is a diagram of a modified arrangement which will permit the marking device to be rendered operative without interrupting the web feeding mechanism; and

Fig. 5 is a more or less diagrammatical illustration of a modified form of marking device.

In the apparatus illustrated in Fig. 1, the web of fiber filler material 10 is fed through an electrical device capable of detecting the presence of metallic particles in the web. This so-called metal detector per se may be purchased in the open market and, of course, is not claimed herein. Hence it has been illustrated only schematically and may be briefly described as comprising an oscillator head 11 and a detector head 12 between which the web 10 is passed. As is well understood in the art of electronics, the oscillator head has two coils, or components, so arranged

35 with respect to each other that the electromagnetic fields produced by currents flowing in the two coils exactly oppose or balance one another so that the effect in the area around the head is the same as if no field were being produced.

40 Thus, under such conditions, no current is induced in the coil of the detector head. The coil of the detector head is in a circuit which contains amplifier tubes and a thyratron or so-called "trigger" tube which, in turn, all as is well known, 45 comprises a cathode and plate and, if the balance between the two coils or components of the oscillator head is disturbed, as for instance, by the presence of a piece of metal in the web being fed through the detector, a current will be induced 50 in the detector head coil and this current am-

plified by the amplifier tubes will result in a current flowing from the cathode to the plate of the thyratron or "trigger" tube. Thus, by incorporating in the plate circuit of the "trigger" tube, a sensitive relay capable of closing proper operating circuits, the action of the detector mechanism can be utilized for controlling the feeding and the marking of the web of fibers to denote the location of metallic objects therein.

Preferably, the web of fibers is supported on a non-metallic or insulated surface 13 and is fed along said surface between the oscillator and detector heads by friction rolls 14, 15, one of which is driven by a sprocket chain 16 from a sprocket 17 on shaft 18 which, in turn, is driven by the electric motor 19. In order that the operator may interrupt the feeding of the web without cutting off the motor, rotary motion is transmitted from the armature shaft 20 of the motor through a worm 21 to a worm gear 22 on shaft 18, and the latter is provided with a clutch mechanism 23, including a clutch lever 24, at a point intermediate gear 22 and sprocket 17 whereby the latter may be manually rendered inoperative by the operator disengaging the clutch elements.

In the preferred construction, the marking device consists of a nozzle 25 located above and directed toward the web of fibers and connected by a supply line 26 with a reservoir 27 containing a suitably colored marking fluid maintained under the desired pressure by a compressed air line 28 connected to the reservoir. Flow of marking fluid from reservoir 27 to nozzle 25 is controlled by a solenoid valve 29 in supply line 26, said valve being actuated as will now be described in connection with the explanation of the wiring diagram of Fig. 3. If it is desired to automatically interrupt the feeding of the web before the marking fluid is applied to the web through nozzle 25, the various instrumentalities are connected electrically as illustrated in Fig. 3. The main feed lines 30, 31, in which there is interposed a main switch 32, are connected by lines 33, 34 to the oscillator and detector heads. The motor circuit consists of lines 35, 36, connected to lines 33, 34, respectively, and to the motor 19 through the contactors of a relay 37 in lines 35 and 36. The coil of relay 37 is indicated at 37^a in the control circuit which consists of line 38 connected between lines 33, 34 and having therein, in addition to coil 37^a, a manually operable, normally open control switch 39, coil 40^a of a relay with contacts 40 in the solenoid circuit, coil 41^a of a relay with contacts 41 in a line 42 for short-circuiting the control switch 39, and the contacts of relay 43, the coil of which is in the plate circuit of the thyratron or "trigger" tube of the detector mechanism previously described. The solenoid circuit is formed by a line 44 connected between lines 33, 34, and preferably includes a manually operable switch 45 in addition to the solenoid 29 and relay contacts 40. The control switch 39 is of the push type normally yieldingly held open by a spring (not shown) while the switch 45 must be opened and closed manually.

Assuming the control switch 39 to be open, contacts of relays 37, 40 and 41 to be open, and the contacts of relay 43 to be normally closed, the operation of the apparatus is as follows: When the main switch 32 is closed the solenoid and detector circuits are energized and when control switch 39 is closed the coils 40^a, 41^a and 37^a will be energized to actuate the corresponding

relays with the result that the motor circuit is closed by relay contacts 37; relay contacts 40 in the solenoid circuit close and relay contacts 41 in line 42 also close. The operator may then immediately release the push button switch 39, and the detector circuit and motor will remain energized through lines 30, 42 and 31, as relay 41 acts as a holding circuit to energize relay coil 37^a and hold its contacts closed. However, the contacts 40 will open as a result of coil 40^a being deenergized, it being remembered that relay 43 is normally closed. Upon the motor 19 being energized, the fiber web starts moving between the oscillator and detector heads and, at this moment, the manual switch 45 should be closed, thus permitting completion of the solenoid circuit whenever relay 40 is subsequently energized. Under these conditions, if a fragment of metal in the web passes between the detector and oscillator heads 20 the former will operate to initiate flow of current in the trigger tube, as previously described, and as the coil of relay 43 is in this circuit its contacts will open. Upon relay 43 being thus opened the control circuit is thus broken so that the coil 37^a of the relay 37 in the motor circuit is deenergized and the motor 19 rendered inoperative. The relay 41 is also deenergized so that holding circuit is opened. Thus, the movement of the fiber web between the oscillator and detector heads is interrupted and will not be resumed until the control switch 39 is again depressed. When this is done the coil 40^a of relay 40 will be energized with the result that the contacts of relay 40 will be closed and switch 45 having previously been closed the solenoid valve 29 will be energized to open the valve thus permitting an increment of marking fluid to be ejected from nozzle 25 onto the surface of the web. By properly positioning the nozzle above the web with regard to the momentum or the rate of movement of the web after motor 19 has been re-energized, it is possible to substantially mark the exact location, longitudinally of the web, of the piece of metal in the web which caused the interruption in the movement of the web. That is, the fragment of metal will be found to be located within a very short distance, probably less than a half inch, of a line extending transversely of the web through the mark applied by the marking device. The discharge of the marking fluid from the nozzle will continue only so long as the operator retains the control switch 39 closed because the moment this switch is released it returns to its open position so that relay 40 is deenergized. However, the holding circuit of relay 41 keeps relay 37 energized so power is supplied to the motor until relay contacts 43 are again opened. Thus, there is what might be described as a more or less instantaneous application of the marking fluid to the surface of the web. It will also be appreciated that once the apparatus is set in motion the solenoid valve is opened each subsequent time that the control switch is closed.

Where it is desired to apply the marking to the web without cutting out the motor the wiring arrangement is such as that illustrated in Fig. 4. In this instance, the main line wires 130, 131, having the main switch 132 therein, are adapted 70 to be connected to the oscillator and detector heads as before and the circuit for motor 190 comprises the line 135 which is connected to the main line wires and has incorporated therein a motor control switch 139 which is manually closed 75 and opened so that it will remain closed until

opened by the operator. The marker mechanism control circuit indicated by line 140 comprises the solenoid 129 for actuating the marking mechanism and the normally open relay 143 whose coil is included in the plate circuit of the thyratron or "trigger" tube. With this arrangement after the main switch 132 has been closed and a sufficient time interval allowed for the filaments of the oscillator and detector heads to become heated the motor circuit is energized by closing the motor control switch 139. So long as the web of material being fed between the detector and oscillator heads contains no metal the relay 143 will remain open but if a piece of metal passes between those detector elements the consequent flow of current from the cathode to the plate of the "trigger" tube will result in relay 143 being closed and thus energizing the solenoid 129 whereupon the marking will be applied to the web. As will be apparent, this closing of the solenoid circuit 140 has no effect upon the motor circuit and hence the web will continue feeding past or through the detector head so that the marker mechanism will be operative only for an instant, or until the piece of metal in the web passes beyond the sensitive zone of the detector mechanism.

In lieu of applying a liquid marker to the web, the marking may be done by imprinting it upon the surface of the web by an arrangement such as is diagrammatically illustrated in Fig. 5. That is, the solenoid 229 may be utilized to actuate a lever 230 carrying a printing or marking head 231 so that as the solenoid is energized the printing or marking head 231 will be moved into contact with the surface of the web.

While the present apparatus has been described in connection with the marking of a web of vegetable fibers to be used as filler material for plastics compositions it will be appreciated that the apparatus can be used for similarly marking any web of non-metallic material regardless of the use to be made of the latter.

What is claimed is:

1. An indicating attachment for a detector apparatus comprising electronic devices having balanced electromagnetic fields responsive to the presence of metallic bodies in the filler material of a plastics molding composition positioned in proximity to said fields, said attachment having, in combination, means for conveying said material in proximity to said fields, means operable by said electronic devices to render said con-

veying means inoperative and arrest actuation of said conveyor means upon detection of a metallic body in said filler material, manually controlled means for rendering said conveyor means operative, holding means actuated by said manually controlled means for holding said conveyor means in operative condition upon release of said manually controlled means, and normally inoperative marking means for applying a marking to said filler material for denoting the location of a metallic body in the filler material, said normally inoperative marking means being rendered operative by the actuation of said manually controlled means to render said conveyor means operative.

2. Apparatus for denoting the location of metallic bodies concealed in a fibrous web comprising a normally inoperative marking device for applying an indicating mark to said web, mechanism for feeding said web past said marking device, power means for driving said feeding mechanism, a motor control circuit for said power means, a manually operable starting switch for actuating said motor control circuit to render said power means operative to drive said feeding mechanism, a holding circuit actuated by said starting switch for holding said motor control circuit in actuated condition after release of said starting switch, a marking control circuit for operating said marking device, said marking control circuit being actuated by operation of said starting switch and rendered inoperative upon release of said switch, and means responsive to the presence of a metallic body in said web for rendering said holding circuit inoperative and thereby stopping said feeding mechanism.
